UNITED STATES PATENT OFFICE

WALTER P. HUNTER, OF VANCOUVER, WASHINGTON

TAKE-UP DEVICE

Application filed May 23, 1929. Serial No. 365,484.

This invention relates to a take-up device for use in connection with brasses carried by a strap for a connecting rod.

As is well known, the breaking of brasses employed for connecting rods is generally caused by the brasses becoming loose from the strap due to wear, resulting in a pounding action which terminates in the breaking of the brasses and it is the object of this invention to provide, in a manner as hereinafter set forth, a device of the class referred to including a take-up gib for retaining the brasses tight in the strap under such conditions greatly reducing, if not entirely eliminating the trouble caused by broken brasses.

A further object of the invention is to provide, in a manner as hereinafter set forth, a device for the purpose set forth whereby take-up of for wear can be expeditiously had by adjusting the gib and then positively locking the latter to adjusted position to maintain the brasses tight within the strap to prevent any possibility of pounding.

A further object of the invention is to provide, in a manner as hereinafter set forth, a take-up device for the purpose referred to including a hardened steel gib interposed between the strap and the brasses and provided with a recess to keep pressure off the brasses at the thinnest point wherein general practice brasses are released on the bearings at such point.

A further object of the invention is to provide, in a manner as hereinafter set forth, a take-up device for the purpose referred to including a lubricant feed so arranged to prevent any possibility of the lubricant feeding between the strap and the brass.

Further objects of the invention are to provide, in a manner as hereinafter set forth, a take-up device for the purpose referred to which is simple in its construction and arrangement, strong, durable, compact, readily installed with respect to the strap, thoroughly efficient in its use, conveniently adjusted, and comparatively inexpensive to set up and further a take-up device that will not interfere with the standard size strap when installed.

With the foregoing and other objects in

view the invention consists of the novel construction, combination and arrangement of parts as hereinafter more specifically described, and as illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary sectional view illustrating the arrangement of take-up device in accordance with this invention with respect to the strap and the brasses.

Figure 2 is a top plan view of the strap and further illustrating the adjusting screws for the gib of the device.

Figure 3 is a fragmentary view in vertical section illustrating the gib and lubricant feed.

Figure 4 is an inverted plan view of the gib.

Figure 5 is a view looking towards one side edge of the gib.

Referring to the drawings in detail 1 denotes a strap carrying brasses 2 in a known manner and 3 indicates a pin.

The inner face of the top of the strap 1 is cut away to provide a transverse groove of appropriate width and which includes a top wall 4 and a pair of side walls 5, 6. The points of emergence of the top wall 4 with the side walls 5, 6 are rounded as at 7. The groove is of appropriate width and has mounted therein a hardened steel gib 8 of a length corresponding to the width of the groove and of a width corresponding to the length of the groove. The side walls of the groove prevent the longitudinal shifting of the gib 8 relative to the top portion 9 of the strap 1.

The upper face of the portion 9 of the strap 1 is formed with a vertically disposed collar 10 provided with interior threads 11 for the purpose of connecting a lubricant supply cup thereto. The portion 9 of strap 1 is furthermore formed with a vertically disposed opening 12 which extends from the in-

ner to the outer face of portion 9 and the purpose of the opening 12 will be presently referred to. The portion 9 of strap 1 is furthermore provided with two pairs of openings, one pair indicated at 13 and the other pair at 14. The wall of each of said openings is threaded. The pair of openings 13 is arranged rearwardly with respect to the opening 12, as well as spaced therefrom and the pair of openings 14 is arranged forwardly 10 of the opening 12, as well as being spaced therefrom. The openings 13 of the pair are arranged in alignment as well as substantially spaced from each other and a like arrangement is had with respect to the openings 14. The opening 12 is arranged at the longitudinal median of the portion 9 of the strap 7 and the openings 13 and 14 are arranged on opposite sides of such longitudinal median.

15 Threadedly engaging with the walls of the openings 13, 14 are combined adjusting and retaining screws 15 for the gib and which bear upon the latter between its transverse median and each end thereof. The screws 15 which extend through openings 13 bear on the gib 8 at two spaced aligning points. The screws 15 which extend through the openings 14 bear on the gib 8 at two spaced aligning points. The screws 15 extend a substantial distance above the top of the strap 7 and carry clamping nuts 16 for rigidly maintaining the screws 15 in set position. The clamping nuts are arranged in pairs and the inner of the nuts bear against the upper face of strap 7. The gib 8 centrally thereof is provided with an opening 17 having a threaded wall and engaging with the threads of said wall is the lower end of a vertically disposed lubricant conducting sleeve or tube 18 which 20 extends upwardly through the opening 12 and provides means for conducting lubricant to the brasses 2 and these latter have lubricant conducting passages 19. The sleeve 18 has peripheral threads on its lower portion only. The sleeve 18 opens into a transverse groove 20 formed in the lower face of the gib 8. The groove 20 is provided in order to keep pressure off the brasses at the thinnest point where in general practice brasses are 25 released on the bearings at this point. This release in the gib can be made any length to suit strength of brass at such point.

The sleeve 18 conducts the lubricant in a manner to the bearing so that the lubricant will not be supplied between the strap and the gib. The sleeve 18 is slidably mounted in the opening 12 and bodily shifts downwardly with the gib 8 when the latter is adjusted through the medium of the screws 15.

The arrangement of the screws relative to the gib 8 provides a means of taking up wear and positively locking the gib throughout when wear is taken up. This eliminates fil-

ing or machining strap as in the general practice when overhauling rods at the present time. The sleeve 18 not only provides for conducting the lubricant to the bearing but also functions to prevent longitudinal and transverse shift of the gib.

It is thought the many advantages of a take-up device in accordance with this invention and for the purpose set forth can be readily understood, and although the preferred embodiment of the invention is as illustrated and described, yet it is to be understood that changes in the details of construction can be had which will fall within the scope of the invention as claimed.

What I claim is:

1. A take-up device for bearing brasses comprising an inwardly shiftable gib adapted to be slidably seated in the inner face of the upper portion of the strap of a connecting rod for abutment against the bearing brasses, combined adjusting and retaining elements bearing against the gib at spaced points and adapted to be carried by the upper portion of the strap, said gib having that face opposing the brasses formed with a transversely extending groove, and a lubricant conducting tube carried by the gib, opening into said groove and slidably extending through the upper portion of the strap for communication with a lubricant supply, said tube bodily carried with said gib.

2. A take-up means for brasses mounted in the connecting strap of a connecting rod, the combination with the top portion of the connecting strap, said top portion having its inner face formed with a transverse groove, of an inwardly slidable hardened steel gib confined to the walls of said groove and adapted to abut the bearing brasses mounted in the strap, a combined adjusting and releasing means for and bearing against said gib at spaced points and threadably engaging with said top portion, and a lubricant conducting tube bodily carried with said gib and slidably mounted in said top portion.

3. A take-up means for brasses mounted in the connecting strap of a connecting rod, the combination with the top portion of the connecting strap, said top portion having its inner face formed with a transverse groove, of an inwardly slidable hardened steel gib confined to the walls of said groove and adapted to abut the bearing brasses mounted in the strap, a combined adjusting and releasing means for and bearing against said gib at spaced points and threadably engaging with said top portion, and a lubricant conducting tube bodily carried with said gib and slidably mounted in said top portion, said gib having its inner face provided with a transverse groove into which opens said conducting tube.

4. In a take-up device for bearing brasses, a bodily shiftable gib acting to maintain brasses tight within a connecting strap and carrying

a lubricant conducting tube projecting outwardly therefrom, said gib having its inner face formed with a groove into which said tube opens.

5 In testimony whereof, I affix my signature hereto.

WALTER P. HUNTER.
